United States Patent Office

Des. 225,664
Patented Dec. 26, 1972

225,664

SEED PLATE ADAPTER

Leonard T. Fleischer, 315 Pershing Road,
Columbus, Nebr. 68601

Filed Mar. 4, 1971, Ser. No. 121,224

Term of patent 14 years

Int. Cl. D15—03

U.S. Cl. D35—2

FIG. 1

FIG. 2

FIG. 3

FIG. 4

FIG. 1 is a perspective view of the seed plate adapter of the invention showing my new design;

FIG. 2 is a top plan view thereof;

FIG. 3 is a bottom plan view thereof;

FIG. 4 is a side elevational view thereof.

I claim:

The ornamental design for a seed plate adapter, substantially as shown.
